UNITED STATES PATENT OFFICE.

CARL WILHELM SÖDERBERG, OF SKI, NEAR CHRISTIANIA, NORWAY.

ELECTRIC INDUCTION-FURNACE.

954,827.

Specification of Letters Patent. Patented Apr. 12, 1910.

Application filed May 15, 1909. Serial No. 496,21

To all whom it may concern:

Be it known that I, CARL WILHELM SÖDERBERG, a subject of the King of Norway, residing at Ski, near Christiania, Norway, have invented certain new and useful Improvements in Electric Induction-Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to electric induction furnaces of the transformer type.

An electric induction furnace theoretically consists of a transformer with short circuit in its secondary coils, the latter mostly consists of one or more liquid metal baths, which replace the coils, the ohmic resistance of which is so adjusted, that a suitable load obtained. It is important, in order to obtain a minimum leakage of the power lines, 20 that the disk transformers have the coils so distributed, that the whole number of ampere-turns is not concentrated to one coil.

The object of my invention is to provide an induction furnace of the disk-transformer type, in which this electrical feature as well as means for facilitating the metallurgical operations are embodied.

In the accompanying drawing a constructional form of apparatus is shown in which: 35 Figure 1 is a horizontal section of the apparatus on the line D—E of Fig. 2 and Fig. 2 is a vertical section of the same on the line A—B in Fig. 1.

The primary windings are distributed on 40 four coils as a_1 , a_2 inclosing both of the vertical parts b_1 and b_2 of the iron core. The secondary armature consists of a metal bath m_1 , m_2 contained in a hearth m arranged between the primary coils and formed with an 45 intermediate portion, and two semi-annular channels e_1 , e_2 , which together with the intermediate portion inclose both of the vertical pieces of the iron core. By the arrangement of four coils the leakage of the power lines is cut down to about one fourth of what 50 it would otherwise have been under similar

circumstances, in known constructions of induction furnaces of the disk-transformer type having iron cores.

The lower primary coils are cooled by currents of air which pass through channels d_1 , d_2 in the foundation of the furnace which may be of masonry or any suitable material as the effect of the intensity of the current is proportional to its square; the above mentioned cooling diminishes the resistance and the intensity of current is increased. The efficiency of the furnace per unit of time thus increases, an advantage which is the more important in this construction, because the 60 coils inclose both of the vertical legs of the transformer.

In order to facilitate the metallurgical operations, which are rendered difficult on account of the primary coil covering part of the metal bath, the extended parts of the bath are situated outside of the current carrying parts of the bath and not covered by the primary coils. Such channels have been used in some prior constructions, but never 75 in furnaces of the disk-transformer type for the above mentioned purposes of providing working space, the metallurgical operations, the feed, and the treatment of the slag are facilitated and repairs may be easily made 80 without removing any part of the primary coils of the furnace.

I claim:

1. In an electric induction furnace, an iron core, a hearth having an intermediate portion and semi-annular ends surrounding the portions of the core that pass through the hearth, a primary coil system comprising two disk coils above the hearth surrounding those portions of the core extending through the hearth, said disk coils being in close proximity to the hearth and covering only the semi-annular portions of the bath in the hearth, thereby leaving the bath in the intermediate portion of the hearth open, and 90 disk coils below the hearth also surrounding the core.

2. In an electric induction furnace, an iron core, a hearth having an intermediate portion and semi-annular ends surrounding the 100 portions of the core that pass through the hearth, a primary coil system comprising

two disk coils above the hearth surrounding those portions of the core extending through the hearth, said disk coils being in close proximity to the hearth and covering only the semi-annular portions of the bath in the hearth, thereby leaving the bath in the intermediate portion of the hearth open, and disk coils mounted below the hearth in channels formed in the furnace, said channels adapted

to permit a current of air to pass around the 10 lower coils.

In testimony that I claim the foregoing as my invention, I have signed my name in presence of two subscribing witnesses.

CARL WILHELM SÖDERBERG.
